(Continued)*Primary Examiner* — Robert M Spear*Assistant Examiner* — Eliza Bennett-Hattan(74) *Attorney, Agent, or Firm* — Intellectual Property Center, LLC; Arthur K. Shaffer(57) **CLAIM**

The ornamental design for protective cap for a bone tool, as shown and described herein.

DESCRIPTION

FIG. 1 is a perspective view of a protective cap for a bone tool in accordance with the present invention;

FIG. 2 is an elevation thereof;

FIG. 3 is a top plan view thereof; and,

FIG. 4 is a bottom plan view thereof.

The broken lines in the drawing depict environmental subject matter only and form no part of the claimed design.
